UNITED STATES PATENT OFFICE.

ABRAHAM REESE, OF PITTSBURG, PENNSYLVANIA.

RAIL FOR STREET-RAILROADS.

Specification of Letters Patent No. 26,523, dated December 20, 1859.

To all whom it may concern:

Be it known that I, ABRAHAM REESE, of Pittsburgh, in the county of Allegheny and State of Pennsylvania, have invented a new 5 and useful Improvement in Rails for Street-Railroads; and I do hereby declare the following to be a full, clear, and exact description thereof, reference being had to the annexed drawing, forming part of the specification, in which—

Figure 1, is a perspective representation of a short section of a rail detached from the sill and with a spike inserted in its spike hole. Fig. 2, is a representation of a similar section of a rail turned over so as to show the face or side which is turned down in Fig. 1.

In both figures like letters of reference denote similar parts of the rails, &c.

20 My invention consists in so constructing rails for street railroads as hereinafter described, both sides or faces being finished alike, so that either side may be turned uppermost, and that when one side of the rail 25 is worn, it may be turned over and used on the other side equally as well as a new rail.

To enable others skilled in the art to make and use my improvement, I will proceed to describe more particularly its construction 30 and advantages.

My rail is designed to be made as is usual, of wrought or rolled iron; it consists of a flat bar of iron *a*, with an elevation *b* or projection of uniform height and width at 35 one edge extending the whole length of the rail on one side, and a similar projection *c* of uniform height and width extending downward at the opposite edge, extending also the whole length of the rail. This 40 makes the plate or bar which composes the rail, thicker at either edge than in the middle, while on either face of the rail, it is a plane surface, either level or slightly inclined from one edge to the projection or 45 head of the rail, at the other edge on which head or projection, the tread of the car wheel travels. Thus both faces of the rail are exactly similar, and present a flat rail with a single projection, and that at one 50 side of the rail. The flat portion of the rail, from the inner edge to the commencement of the head or projection, had better be a plane surface, because that portion on one face of the rail, lies on top of the longitudinal sill of the road, and has a better bearing if it be flat. The head of the rail on

either side (*b* or *c*) is but slightly elevated above the flat part or base of the rail, as the flange of the car wheels used on passenger or street railways, projects much less beyond the tread of the rail, than in wheels used on ordinary rail roads.

My improved rails are designed to be laid with the base or flat portion of the under-side or face of the rail on the longitudinal wooden sill of the road, with the shoulder formed by the projection or head *c* on the under side of the rail pressing against the side of the wooden sill; or if it be preferred that the longitudinal sill should extend under the whole width of the rail a rabbet or depression is cut on the inner edge of the sill to receive the lower projection or head *c*, all on the base of the rail to rest on the sill, which answers the same purpose of giving 75 the rail a lateral bearing against the inner side of the longitudinal sill, caused by the well known inclination of the car wheels to press outward against the side of the rails. This bearing of the under projection or 80 head *c* of the rail against the inner edge of the longitudinal sill, enables the rail to resist the outward pressure of the car-wheels, and prevents the spreading of the rails. This is equally the case whichever face of 85 the rail is turned upward.

The holes in the rails for driving the spikes to fasten the rails to the sills, are placed to one side of the central line of the rail. There are two sets of spike holes in 90 each rail, one set designed to be used when the rail is used one side up, and the other set when the rail is reversed. These holes are countersunk, to receive the head of the spike, one set of holes marked *d* Fig. 2, being countersunk on the side of the rail which will be uppermost when those holes are to be used, and these holes are situate nearer the inner than the outer edge of the rail, as seen in Fig. 1, and so that when the wheel of the 100 car passes over the rail, it does not pass over the heads of the spikes by which the rail is secured. These holes *d* are not countersunk on the under face of the rail, which is turned up in Fig. 1. The other set of spike holes 105 marked *e* are situate nearer to the other edge of the rail than the central line, and are countersunk on the opposite face of the rail to that on which the holes *d* are countersunk, as will be seen by comparing Figs. 1 110 and 2.

Rails thus constructed possess very great

advantages for street railways over any other rails with which I am acquainted, and I will briefly enumerate a few of these advantages. They are more easily rolled than rails of ordinary construction, as both edges are of the same thickness, for when one edge of the rail is thick and the other thin, the thin edge is apt to crack in rolling. But the chief advantage of the mode of constructing rails hereinbefore described, is their practical utility for street railways in the following particulars: They present less than ordinary obstruction to the wheels of carriages, carts and other wheeled vehicles used in the streets of cities. That the head or projection of the rail which is turned down, pressing against the side of the sill, prevents the spreading of the track, and greatly relieves the lateral strain on the spikes, and that when the head of the rail is worn out on one side by the tread of the car wheels and by the transverse passage of other wheeled vehicles in crossing the track, the rail may be reversed, and used the other side up for as long or nearly as long as it was used before one side was worn out; thus making the rails wear almost, if not quite twice as long as

rails of ordinary construction; the reversed rail being as good as new, because the head of the rail which is turned up on the reversal of the rail, was previously turned down, and at the inner edge of the track, and not liable to injury.

Having thus described my improved rail for street or passenger railways, what I claim as my invention and desire to secure by Letters Patent, is—

Making iron rails for street railways, of the shape substantially as hereinbefore described, having on each side a head or projection at one edge of the rail, with a flat base extending from the projection or head to the other side, both sides or faces being finished alike, so that the rail may be used either side up, and reversed when one side is worn out.

In testimony whereof, the said ABRAHAM REESE hath hereunto set his hand in presence of us.

ABRM. REESE.
